UNITED STATES PATENT OFFICE.

ROBERT BLANK, OF COLUMBUS, OHIO, ASSIGNEE TO SOLAR-STURGES MFG. CO., A CORPORATION OF ILLINOIS.

FIREPROOF WASTECAN.

Application filed July 14, 1921. Serial No. 484,722.

To all whom it may concern:

Be it known that I, ROBERT BLANK, a citizen of the United States of America, residing at Columbus, in the county of Franklin and State of Ohio, have invented certain new and useful Improvements in Fireproof Wastecans, of which the following is a specification.

My present invention relates generally to receptacles and more particularly to a metallic fireproof waste can, capable of manufacture in a variety of sizes for various uses, my object being the provision of a fire-proof receptacle of that nature adapted 10 as a garbage or waste can for house, factory, street, park and other uses.

Generally speaking my invention consists of a can which embodies a readily opening door together with means whereby this door 20 is normally held in closed position so as to prevent communication of fire either to the contents of the can or from the contents to the exterior of the can.

The present form which my invention 25 takes is shown in the accompanying drawing, which forms a part of this specification, and in which

Figure 1 is a side view,

Figure 2 is an enlarged vertical section 30 taken therethrough,

Figure 3 is a bottom plan view of the cover removed,

Figure 4 is a view similar to Figure 2 showing one of the doors in open position, 35 and

Figure 5 is a detail sectional side view illustrating a slightly modified form of door controlling lever.

Referring now to these figures my invention 40 proposes a can including an upright cylindrical body 10, the shape of which lends itself to ready convenient and cheap manufacture, having an upper open end and an inturned annular reinforcing lip 11 45 around said upper end, the body being preferably of one diameter throughout.

The base or bottom plate 12 as shown particularly in Figure 2, may be either flat or of the concavo-convex form illustrated, and 50 is preferably provided with a flanged edge 13 adapted to telescope the lower end of the body 10 and receive therein a reinforcing ring 14 of heavier material, whose lower edge 15 depends slightly below the coin-

ciding lower edges of the body 10 and the 55 base flange 13.

The cover 16 is preferably of substantially the semi-globular form shown, with its lower enlarged open end provided with an offset annular flange 17 adapted to telescope the reinforced upper edge of the can body, flange 17 of the cover preferably terminating in a rolled rib 18 for strengthening purposes. At its upper central portion, the cover 16 has an upward projecting 60 pressed integral cap 19 which includes an annular wall 20 forming a support for brackets 21 to which the upper ends of the upper inner sections 22 of door controlling levers are hinged at 23.

At opposite points, the cover has door openings 24 whose lower and side edges are preferably reinforced by inturned lips 25, and into these openings doors 26, curved to conform to the curvature of the cover, are 75 yieldingly held in seated relation at all times. These doors 26 are connected by hinges 27 disposed at their upper edges and secured to the upper inner portion of the cover, the lower edges of the door having 80 inward curved lips 28 which engage the adjacent reinforced edges of the door openings.

The doors 26 are also provided on their inner surfaces and adjacent to their lower edges with brackets 29 to which the lower 85 outer ends of the lower sections 30 of door controlling levers are pivotally connected at 31.

The lower ends of the upper lever sections 22 and the upper ends of the lower 90 lever sections 30 are pivotally connected at 32, and these pivoted ends of the lever sections are preferably enlarged as shown to form weights 33 which, through gravity, 95 serve to hold the doors 26 in the closed position shown in Figure 2, in such manner that either or both of the doors may be pressed inward to the open position shown in Figure 4 in order to permit ingress to the can body.

In order to improve the lateral rigidity of the door actuating lever mechanism by lengthening the hinge axes, each lower section 30 preferably includes two spaced arms connected by a web, and the upper section 10 is used in duplicate, there being two sections 22 for each door. This is most clearly shown in Figures 3 and 4. Figure 4 also

shows how the two lever mechanisms are staggered relatively to each other so that when either door is, or both doors are, opened the lever mechanisms clear each other 5 by straddling. This last feature permits the use of larger doors and greater opening movement of the doors than could otherwise be had.

As shown in Figure 5 each door controlling lever may include an upper section 34 pivoted to the cover and provided with a weight 35 adjacent to its lower end. This lower end is hinged at 36 to the upper end of the lower section 37 pivotally connected 15 to the door it controls, so that one only of the sections carries the weight instead of the sections cooperating to form the weight as previously described.

The can or receptacle as a whole may be 20 transported from place to place by virtue of the provision of handles 38 at diametrically opposite sides of the body 10 adjacent to its upper open end, or a bail as shown in dotted lines in Figure 1 may be utilized in 25 hinged relation to the can body for the same purpose.

In any event it is obvious that under normal circumstances the can or receptacle will be maintained in completely closed condition 30 with the cover in place, by virtue of the automatically closing doors, and it is likewise obvious that under normal circumstances the means utilized for maintaining the doors closed will be housed and protected from external influences and in this way maintained 35 in properly and effectively operating condition at all times.

I claim:

1. The combination of a container having 40 a side opening; an inward opening door piv-

oted to the container, and when closed seating against the margin of said opening; and gravitating levers mounted within the container, pivoted to each other and one pivoted to said door and the other to a part of 45 said container, said levers being constructed and arranged to hold said door yieldingly closed by the action of gravity.

2. A waste can comprising in combination a body open at its upper end; a cover resting 50 upon and projecting above said body, and formed with a side opening; a door hinged at its upper edge to said cover and when closed seating outward against the margin of said opening; and gravitating 55 levers pivoted to each other and pivoted one to the door and the other to the upper central portion of said cover, said levers being constructed and arranged to hold said door closed by the action of gravity. 60

3. A waste can comprising in combination a body open at its upper end; a cover resting upon and projecting above said body and formed with opposed side openings; inward 65 opening doors hinged at their upper edges 70 to said cover and serving to close respective openings; and two sets of gravitating levers, one for each door, said sets being offset to straddle each other in their movements with the doors and each set including two levers 75 one pivoted to the door and to the second lever and the second pivoted also to the cover, said sets of levers being arranged to swing in substantially vertical planes and to urge the corresponding doors closed by the action of gravity.

In testimony whereof I have affixed my signature.

ROBERT BLANK.
